UNITED STATES PATENT OFFICE.

FELIX STAHL, OF NUEREMBERG, GERMANY, ASSIGNOR TO LEO SIMON, OF NUEREMBERG, GERMANY.

WOOD PEG OR FASTENER FOR WOODEN RAILWAY-SLEEPERS OR THE LIKE.

SPECIFICATION forming part of Letters Patent No. 698,070, dated April 22, 1902.

Application filed February 16, 1901. Serial No. 47,649. (No model.)

To all whom it may concern:

Be it known that I, FELIX STAHL, a subject of the German Emperor, residing at Nu-
remberg, Bavaria, German Empire, have in-
5 ventioned Improvements in Wood Pegs or Fast-
eners for Wooden Railway-Sleepers or the
Like, of which the following is a specification.

In the fastening of railway-rails on wooden
sleepers it is usual to surround the means for
10 fastening the rail to the wooden sleeper with a
layer of longitudinal fiber—that is to say, a
wood plug or peg—in order to afford a better
hold to the means of attachment and for forming
15 a water-tight joint for the space remaining
between the perforation in the sleeper and the said peg. The attempt has hitherto
been made to obtain this result by a very
short enlargement of the diameter of the head
20 of the peg in such a way that the thickened
head when the peg is driven or screwed into
the sleeper wedges open the perforation. In
sleepers of unequal thickness or which are
25 cut out with an adz it has been disagreeably
noticeable that the ends of the peg project be-
yond the under surfaces of the sleeper, as the
enlarged part at the head must be forced into
30 the perforation. The projecting ends have
then to be sawed off in order to protect the
peg from great disturbances when the track
is pushed into place or straightened. A sec-
35 ond drawback of this kind of wood plugs con-
sists in that the longitudinal fibers of the
wood plug standing vertically on the ground
eagerly attract, by reason of their capillarity,
40 the moisture from the ground, and thus the
effect sought to be obtained by the use of
wood plugs is partially destroyed.

The attempt has been made to remove the
first drawback in the present invention by
45 making the peg a screwed one, which on its
outer surface is provided with a long and
thick cone between its under threaded part
and its head, which is to be rasped off. By
50 this formation of the peg-head, which lies
against a corresponding elongated conical
inner surface of the perforation in the wood
sleeper, a water-tight and firm closing of the
perforation in the sleeper is obtained even
55 where the wood sleeper is deeply cut out with
an adz, as in each case the lower part of the
peg-cone is in contact with the conical inner

surface of the perforation in the sleeper
lying still beneath the adzed-out part without
the under end of the peg projecting below the
under surface of the sleeper. The second of 55
the drawbacks hereinbefore mentioned is re-
moved by a peculiar fastening formed on the
under side of the peg, which is arranged in
such a way that on the one hand it prevents
moisture from rising from the ground and on 60
the other hand allows rain, snow, or water en-
tering into the hollow chamber or part of the
peg from above to run off.

This improved wood peg is shown in the
accompanying drawing. As may be seen 65
therefrom, between the lower threaded part *a*
and the headpiece *b*, which is to be cut or
rasped off, there is a comparatively rapidly
widening cone *c* of considerable length.
When the screw-peg is tightened up, the lower 70
part of the cone *c* encounters a correspond-
ing conical inner surface in the perforation in
the sleeper and fits firmly against the inner
surface in such a way that it forms an im-
permeable solid joint against water. Simul- 75
taneously the longitudinal fibers of the peg
itself are thereby firmly pressed together and
form in this way a strong layer or bed, in which
a means of fastening finds an excellent hold.
On the lower end of the screw-peg *a* a metal 80
cap *d* is then fitted, the interior cylindrical
part *e* of which projects into the bore of the
peg and in this manner covers all the parts
of the outer and inner surface of the lower end
of the peg, so that the absorption of moisture 85
by means of the lower ends of the wood fibers
of the screw-peg is prevented. The upper
edges *f* of the cylindrical part *e* of the metal
cap are bent round and are funnel-shaped
downward, so that any rain-water accumulat- 90
ing in the longitudinal boring of the screw-
peg and running down the same cannot reach
the lower ends of the wood fibers, but runs
out freely to the outside through the opening
formed by the funnel-shaped edges. The use 95
of this fastening-cap affords thus three advan-
tages—namely, of preventing moisture from
rising from the ground into the wood peg, of
keeping snow and rain-water away from the
lower ends of the wood fibers, and finally of 100
carrying off such water freely into the ground.

Having now particularly described and as-

certained the nature of my said invention and in what manner the same is to be performed, I declare that what I claim is—

- 5 1. A form of construction of the wood peg such as described which consists in the lower end being covered by a cap *d* fitted thereon in order to protect it against moisture arising from the ground, substantially as hereinbefore described and shown.
- 10 2. A form of construction of the wood peg such as described which consists in the inner part *e* of the closing-cap, which inner part projects into the longitudinal boring of the

wood peg, being formed at its upper end into a funnel *f* which on the one hand prevents 15 the rising of moisture from the ground, and on the other hand allows rain or snow water, which penetrates from above, to run away, substantially as hereinbefore described and shown.

In witness whereof I have hereunto set my hand in presence of two witnesses.

FELIX STAHL.
